(57) **CLAIM**

The ornamental design for a garden patio paver, as shown and described.

DESCRIPTION

FIG. 1: is a perspective top, front and first side edge view of a garden patio paver showing the design applied thereto;

FIG. 2: is a perspective bottom, front and first side respective view thereof;

FIG. 3: is a top plan view thereof;

FIG. 4: is a bottom plan view thereof;

FIG. 5: is a front elevational view thereof;

FIG. 6: is a rear elevational view thereof;

FIG. 7: is a first side elevational view thereof; and,

FIG. 8: is a second side elevational view thereof.

The broken lines shown in the drawings showing the top surface pattern of the garden patio paver form no part of the claimed design.
